(57) **CLAIM**

The ornamental design for a three drawer plastic cabinet, as shown and described.

DESCRIPTION

FIG. 1 is a perspective view of the three drawer plastic cabinet of the instant invention;

FIG. 2 is a front elevation view thereof;

FIG. 3 is a right side view thereof, the left side view forming a mirror image thereof;

FIG. 4 is a rear elevation view thereof; and,

FIG. 5 is a top view thereof.
